(57) **CLAIM**

The ornamental design for a dental appliance holder, as shown and described.

DESCRIPTION

FIG. 1 is a perspective view of a dental appliance holder of the present invention;

FIG. 2 is a front plan view of the dental appliance holder shown in FIG. 1;

FIG. 3 is a rear plan view of the dental appliance holder shown in FIG. 1;

FIG. 4 is a right side view of the dental appliance holder shown in FIG. 1;

FIG. 5 is a left side view of the dental appliance holder shown in FIG. 1;

FIG. 6 is a top plan view of the dental appliance holder shown in FIG. 1;

FIG. 7 is a bottom plan view of the dental appliance holder shown in FIG. 1;

FIG. 8 is a perspective view of the dental appliance holder shown in FIG. 1 in an opened position;

FIG. 9 is a front plan view of the dental appliance holder shown in FIG. 8;

FIG. 10 is a rear plan view of the dental appliance holder shown in FIG. 8;

FIG. 11 is a right side view of the dental appliance holder shown in FIG. 8;

FIG. 12 is a left side view of the dental appliance holder shown in FIG. 8;

FIG. 13 is a top plan view of the dental appliance holder shown in FIG. 8;

FIG. 14 is a bottom plan view of the dental appliance holder shown in FIG. 8;

FIG. 15 is a perspective view of the dental appliance holder shown in FIG. 8 with at least one dental appliance;

FIG. 16 is a perspective view of the dental appliance holder shown in FIG. 1 in an alternate opened position; and,

FIG. 17 is a perspective view of the dental appliance holder shown in FIG. 1 in another alternate opened position.

The broken lines immediately adjacent the claimed areas represent the bounds of the claim, and all other broken lines are included for the purpose of illustrating portions of the present invention that form no part of the claimed design. None of the broken lines form part of the claimed design.
